UNITED STATES PATENT OFFICE.

HARRY M. YINGST, OF HARRISBURG, PENNSYLVANIA.

ADVERTISING DEVICE.

1,352,336.

Specification of Letters Patent.

Patented Sept. 7, 1920.

Application filed March 15, 1920. Serial No. 365,977.

To all whom it may concern:

Be it known that I, HARRY M. YINGST, a citizen of the United States, residing at Harrisburg, in the county of Dauphin and State of Pennsylvania, have invented new and useful Improvements in Advertising Devices, of which the following is a specification.

The present invention is in the nature of 10 a novel advertising device.

The object is to arrange in a transparent body an element having printed matter thereon which is protected by the body and in which the characters appearing on the 15 said element are rendered clearly discernible.

A further object is to produce a novel advertising means which comprises a member having printed matter or other indicia thereon and which is of a nature to permit of the 20 same being inserted in a transparent receptacle, such as a glass bottle and held immovably therein.

The foregoing objects, and others which 5 will appear as the nature of the invention is better understood, may be accomplished by a simple construction, combination and arrangement of parts such as is disclosed by the drawings.

In the drawings:—

0 Figure 1 is a front view of the improvement.

Fig. 2 is a rear view thereof.

Fig. 3 is a sectional view approximately on the line 3—3 of Fig. 1.

In the drawings I have illustrated a bottle or flask of clear glass which is indicated by the numeral 1.

The advertising novelty comprises an elongated member 2 which has secured thereto a shorter transverse member 3. The members 2 and 3 may be in the nature of strips of cardboard, celluloid, rubber or any other desired material, and the connecting means between the strips is in the nature of a double headed rivet which is indicated by the numeral 4. The heads of the rivet are round and lightly bind against the outer faces of the strips. The strip 2 is of a length to rest on the bottom of the member 1 and to be received in the neck thereof. The portion of the strip received in the neck is contacted by the cork or stopper 5 of the member 1, so that the strip 2 is held centrally and longitudinally in the member 1.

The strip 3 is of a length to have its ends 55 frictionally contact with the inner side walls of the flask 1. When the device is inserted in the flask, the strip 3 is preferably swung on its pivot against the strip 2. When the lower end of the strip 2 contacts with 60 the bottom of the flask, a suitable instrument is employed for contacting with the strip 3 to swing the same on its pivot and bring the ends thereof in frictional engagement with the inner side walls 65 of the flask. The cork is then inserted in the mouth of the flask, and engaging with the outer end of the strip 2 holds the device set up approximately centrally in the flask in the form of a cross. As previously 70 stated the heads of the rivet lightly contact with the members constituting the cross, but such contact is sufficient to prevent the free turning of one of the members on the other. Of course, the cross may be inserted in the 75 flask in a different manner from that described, as for instance when the cross is constructed of yieldable material the transverse arm or strip thereof may be rounded upon itself and readily inserted through the 80 neck of the bottle, and thereafter permitted to expand to its original shape, which will bring the ends thereof into frictional engagement with the side walls of the bottle 85 and only a slight adjustment may be required by a suitable instrument to arrange the transverse arm at a right angle with respect to the vertical arm.

In the construction disclosed by the drawings I have imprinted on the lateral or transverse member on one face of the cross 90 "John Barleycorn." On the vertical or central member 2 of the cross I have imprinted "Died Jan. 16, 1920." This indicia will serve as a reminder to both ourselves 95 and posterity that alcoholic beverages received their death warrant on January 16, 1920, and the cross will indicate that Christianity was the cause of the demise of alcoholic drinks, and also that the cross takes 100 the place of such drinks. Thus posterity will be taught that the cross and whisky could not successfully exist together and that the cross was successful over the whisky.

105 On the reverse side of the cross there is printed "Wake up, John is dead but we have a supply of soft drinks." It will be thus

seen that while the improvement teaches an impressive moral lesson, the advertising value thereof is not in any way impaired.

Having thus described the invention, what

5 I claim is:—

In combination with a transparent hollow body, including a neck that is normally closed by a cork; of a cross-shaped member arranged in the body and having indicia im-
10 printed thereon which is readable through the body, the longitudinal element of the

cross-shaped member having one of its ends contacting with the bottom of the body and its other end received in the neck and contacted by the cork in the neck, the trans- 15
verse member of the cross having its ends contacting with the sides of the body for holding the cross against lateral movement in the body.

In testimony whereof I affix my signature. 20

HARRY M. YINGST.
